UNITED STATES PATENT OFFICE.

DAVID WILLIAMSON, OF NEW YORK, N. Y.

IMPROVEMENT IN THE MANUFACTURE OF METALLIC CARTRIDGE-CASES.

Specification forming part of Letters Patent No. 92,136, dated June 29, 1869.

To all whom it may concern:

Be it known that I, DAVID WILLIAMSON, of the city and State of New York, have invented and made an Improvement in the Manufacture of Metallic Cartridge-Cases; and I do hereby declare the following to be a full, clear, and exact description of the said invention, reference being had to the annexed drawing, making part of this specification.

In the manufacture of metallic cartridge-cases they have in some instances been made with a rounded rear end and a central teat to contain the fulminate.

In making these cartridges the teat has been pressed up partially in each of the finishing operations, hence the teat has been of hardened copper, consolidated and stiffened by the action of the dies in finishing the case. In practice it is found that the teat being thus made of hardened metal and round, there is not power enough in most hammers of firearms to explode the fulminate contained in said teat, and the metal cannot be annealed after the last operation of the dies, or else the cylindrical portion of the case would be too soft for the subsequent handling, or to withstand the concussion in firing.

To obviate the aforesaid difficulty in exploding the fulminate, the teat has been flattened, but this involves the necessity of placing the cartridge in the chamber with the flattened portion in one direction. This is difficult to do, particularly in the dark or when in a hurry.

The nature of my said invention consists in the manner of making the said cartridge so that the teat for the fulminate is very soft and easily indented by the hammer to produce the explosion, and, at the same time, the case itself is rendered as hard and solid as usual in cases of this character.

To effect these objects I employ dies that are

formed so as to produce the hollow teat in the sheet metal complete, previous to the annealing of the sheet metal the last time, after which the dies are employed only to stretch, reduce, and harden the sides of the sheet-metal case, leaving the teat in the soft condition in which it remains after annealing.

In the drawing, Figure 1 shows the cartridge-case in one of the first stages in which it is made by the dies, the teat *a* being partially pressed up. Fig. 2 represents the cartridge-case in a second or subsequent stage, with the teat formed completely. At this stage of the manufacture, the shell is thoroughly annealed, and the subsequent operation or operations do not compress or act on the metal of the teat, hence it is left sufficiently soft to be compressed freely by a blow on the side with the hammer of an ordinary fire-arm. In Fig. 3 the cartridge-case is shown complete by the cylindrical portion being drawn down to the proper size by dies, which, at the same time, harden and stiffen the metal forming the cylindrical portion of the case.

The trimming off of the mouth or end of the metallic cartridge-case is performed in any usual manner.

What I claim, and desire to secure by Letters Patent, is—

A sheet-metal cartridge-case, formed with a teat, the metal of which is soft, and with cylindrical sides, the metal of which is hardened by the action of the dies, as and for the purposes set forth.

In witness whereof I have hereunto set my signature this 17th day of March, 1869.

DAVID WILLIAMSON.
